UNITED STATES PATENT OFFICE.

ISADORE J. FAGGEN, OF NEW YORK, N. Y.

STAND AND PAD.

Application filed February 27, 1922. Serial No. 539,485.

To all whom it may concern:

Be it known that I, ISADORE J. FAGGEN, a citizen of the United States, and a resident of the borough of Manhattan, city, county, and State of New York, have invented a certain new and useful Stand and Pad, of which the following is a specification.

My invention relates to devices for storing, holding or retaining hand stamps, cuts, casts, moulds or other stamping, engraving or printing devices, and more particularly for holding hand stamping devices having rubber type, and which are inked by contact with a pad saturated with ink.

15 My invention comprises a novel, unique and compact holder and inking device.

One of the objects of my invention is to provide a device in which a plurality of stamps or other devices are stored, retained 20 or carried.

Another object of my invention is to provide a receptacle for holding rubber stamps having an inking device.

Another object of my invention is to provide a combined stamp holder and pad in which the stamps and the pad will be protected from injury and from dirt or dust.

Another object of my invention is to provide a pad which is readily removable, and 30 which may be easily renewed.

Another object of my invention is to provide a holder in which the type surfaces of the rubber stamps will normally rest upon the surface of the pad.

35 Another object of my invention is to provide a holder in which the type surfaces of the rubber stamps will normally be held out of engagement or contact with the surface of the pad.

Another object of my invention is to provide a holder in which the stamps will be retained in position but may be readily removed, and in which the identity of the 40 stamps will be disclosed.

45 A further object of my invention is to provide a holder in which the stamps can only be inserted in their proper place or position with the identification mark facing in the proper direction.

50 A further object of the invention is the provision of means of the character herein described, compact and simple in construction, thoroughly reliable and efficient in its purpose, inexpensive to manufacture, and neat and attractive in appearance.

With these and other objects in view to be

more fully set forth hereinafter, the invention consists in the novel construction, combination of elements, and arrangement of parts which will be exemplified in the construction hereinafter described in the specification and illustrated in the accompanying drawings considered together or separately.

60 The inventive idea involved is capable of receiving a variety of mechanical expressions, some of which, for the purpose of illustrating the invention, are shown in the accompanying drawings.

The invention will be first described in connection with the accompanying drawings, 70 wherein similar reference characters are used to designate corresponding parts throughout the several views, and then more specifically defined and indicated in the appended claims.

75 In the drawings:—

Figure 1 is a perspective view of a device embodying my invention.

Figure 2 is a longitudinal section on the line 2—2 of Figure 1, with the cover in 80 position.

Figure 3 is a transverse section of the same showing a modification of my invention.

Figure 4 is a detail plan view showing 85 another modification of my invention.

Figure 5 is a detail sectional view showing a further modification of my invention.

Figure 6 is a perspective view showing 90 another modification of my invention.

Figure 7 is a longitudinal section on the line 7—7 of Figure 6, with the cover in 95 position.

Figure 8 is a transverse section of the same on the line 8—8 of Figure 6 with the stamp in position shown in dotted lines.

In carrying out my invention, I provide in one form of my invention a rectangular container, box or receptacle 1 open at the top and having the upper edges of the walls 100 thereof rabbetted to receive a top or cover 2. The rabbets are formed by means of a frame 3 open at the top and bottom thereof and secured within the box 1 with the walls of the frame projecting above the side of 105 the box 1. The frame 3 does not extend to the bottom of the box 1 thus forming a pocket 4 in the lower portion of the box. One of the end walls of the box is cut away, as at 5 whereby the pocket 4 will be accessible from outside of the box.

110 The frame 3 is provided with transverse

end members 6 and with a plurality of spaced, intermediate transverse partitions 7 whereby a plurality of pockets 8 are formed in the frame. The partitions 7 are 5 preferably the same depth as the walls of the frame, as shown. Each of the end members 6 and partitions is preferably concaved on its upper edge as shown at 9.

Slidably mounted in the pocket 4 is a 10 tray or drawer 10, the front wall 11 of which is flush with the end wall of the box 1 having the opening 5, whereby said opening will be closed when the tray is in position. Within the tray 10 is a pad 12 such as is ordinarily used for inking rubber stamps. The tray 10 is provided with a handle 10^a.

As shown in Figures 2 and 3 the side and end rails of the tray project above the surface of the pad, while in the embodiment of 20 the invention illustrated in Figure 5, the said rails are flush with the top surface of the pad.

Each of the pockets 8 is adapted to receive a stamping device comprising a handle 13 and a type surface 14. The handles are of a length sufficient to fit more or less closely the transverse dimensions of the pockets. The upper portions 15 of the handles are more or less cylindrical longitudinally of 30 the handles and of somewhat greater width than the bodies, whereby the edges 15 will properly fit the longitudinal dimensions of the pockets and prevent rattling of the stamping device in the pockets, and the said members are so proportioned as to permit the type surface to come in contact with the pad but not to rest heavily thereon, this being accomplished by making the members of sufficient width so that the point *a* will 35 rest on top edge of one partition and the point *b* will rest on top edge of the adjacent partition. The upper portion 15 of each handle is provided with a flattened surface 16 on which will be impressed a legend corresponding to the type 14 of that particular handle.

The concavities 9 of the rails 6 and partitions 7 will permit the fingers of the operator to reach beneath the enlargements 15 whereby the stamps may be readily removed from the pockets.

When the stamps are positioned in the rack as shown, the type surfaces will lightly rest upon the surface of the pad and the type will always be inked.

In the embodiment of the invention shown in Figure 2, the rear end rail of the pad tray 10 will prevent the withdrawal of the tray while the stamps are in position. When 60 it is desired to withdraw the tray from the box to renew the ink on the pad, all of the stamps must be removed from the pockets. When it is desired to withdraw the tray partially from the box whereby the stamp in 65 use may be reinked without placing it in a

pocket in the box, the stamp farthest from the opening 15 is removed from its pocket, and the tray may then be withdrawn until it is arrested by the engagement of the rear rail thereof with the stamp in the next 70 pocket.

As shown in Figure 5 the top of the pad is flush with the rails of the tray, and with this construction the tray may be withdrawn from the box without removing the stamps. 75

As shown in Figure 3 a leaf spring 17 may be positioned in one or both ends of the pockets whereby the stamps will be retained in position within the pockets, even should the box be inverted; the stamps being held 80 in position by frictional engagement with the springs, and as is obvious, the stamps may be in contact or out of contact with the pad, as desired.

In the modification illustrated in Figure 4 the end walls of the pockets 18 are inclined as shown at 19, and the ends 20 of the handles 21 are beveled, whereby said handles can only be placed in the pockets with flattened surfaces 22 facing in the desired direction. It will be apparent that the resilient means hereinbefore described adapted to provide frictional engagement between the receptacle and the stamp would in this case be applied to the inclined side walls 19 in the same manner that said resilient members are applied to the straight side walls in the Fig. 1 device. 95

It is to be understood that the rack 3 may contain one or any number of pockets. 100

In the modification shown in Figures 6, 7 and 8, I have omitted the pad, thereby utilizing the stand 1 solely as a receptacle for holding rubber stamps. The frame 3, the end members 6 and the intermediate transverse partitions are made of rubber or other resilient or elastic material. The frame 3 is provided with side walls 3^a which are in the form of a segment of a circle, as clearly shown in Figure 8. With such a structure 110 the stamp 15 is held in position by frictional engagement at the point 3^b with the curved surface 3^a of the frame 3. If desired, the entire stand can be made of rubber or other 115 elastic material. It is obvious that this method of providing frictional engagement may be applied to the side walls 19 of Fig. 4 in exactly the same manner as to the side walls of the Fig. 1 device. 120

This method of retaining the stamps can be utilized with the holder provided with the ink pad as shown in Figure 1, but with the rubber or resilient side walls the stamps can be, as is obvious, so positioned as to be out of contact with the pad. If desired, the stand and stamps can be so arranged and constructed that a particular stamp must always be inserted in the same pocket and can only be inserted in said pocket, with the identification mark facing in the proper di- 125 130

rection. One way of accomplishing the foregoing is to provide the frame 3 with sockets or recesses and the stamps with corresponding projections to rest or fit in said sockets or recesses. Said sockets and projections being so constructed, arranged and positioned, that they differ positionally for each pocket and stamp, thereby making it impossible to replace a stamp except in the proper 10 pocket facing in the desired position.

It is obvious in view of the foregoing that I have devised a very unique, compact, serviceable and durable device, in which the rubber stamps are so arranged and constructed as to be always held in proper position, ready for use, and having indicating means which will indicate the characters corresponding to the type on the rubber stamp, such indicating means being so 20 affixed to the rubber stamp that they must always face the person who is to use the stamp, thereby obviating the necessity of picking out the various stamps and looking at the rubber type to see what particular 25 stamp is desired.

While I have illustrated and described my invention in connection with a rubber stamp, I wish it understood that my invention is not so limited, as I use herein the term 30 "rubber stamps" in the generic sense as defining any kind of means for accomplishing the desired results.

The operation of the device is obvious from the foregoing description.

35 In accordance with the provisions of the patent statute, I have described the principle of my invention together with the apparatus which I now consider to represent the best embodiment thereof, but I desire 40 it understood that my invention is not confined to the particular form of apparatus herein shown and described, the same being merely illustrative, and that the invention can be carried out in other ways without 45 departing from the spirit of my invention, and, therefore, I claim broadly the right to employ all equivalent instrumentalities coming within the scope of the appended 50 claims, and by means of which objects of my invention are attained, and the new results accomplished, as herein set forth, as it is obvious that the particular embodiments herein shown and described are only some of many that can be employed to attain these 55 objects and accomplish these results.

Having now described my invention, what I claim and desire to secure by Letters Patent is as follows:

60 1. In a device of the character described, comprising a receptacle adapted to receive a member having a type surface and a sliding member carried by said receptacle, said receptacle being adapted to support said member independently of but in contact with 65 said sliding member.

2. A device of the character described, comprising a receptacle having compartments each adapted to receive and support a member having a type surface and resilient means for retaining said member in position. 70

3. A device of the character described, comprising a receptacle having compartments each adapted to receive and support a member having a type surface and spring members for retaining said member in position. 75

4. A device of the character described, comprising a receptacle adapted to receive and support a plurality of members having type faces and resilient means for retaining 80 said members in position.

5. A device of the character described, comprising a receptacle adapted to receive and support a plurality of members having type faces and spring members for retaining 85 said members in position.

6. In a device of the character described, a printing member and an inking surface, and means positioned beyond said surface for supporting said member in contact with 90 said surface.

7. In a device of the character described, a printing member and an inking surface, and means engaging said member beyond said surface for supporting said member in 95 contact with said surface.

8. In a device of the character described, a receptacle having a plurality of partitions, and a member having a type surface, said member having an enlarged upper portion 100 adapted to engage adjacent partitions to support the member thereon, said partitions having cut-out portions to permit grasping said member beneath said enlarged portion.

9. In a device of the character described, a receptacle having a plurality of upstanding partitions and having an inking surface in the bottom thereof, and a member having a type surface, said member having an enlarged portion adapted to engage adjacent 110 partitions to support said member thereon with the type surface in contact with said inking surface.

10. In a device of the character described, a receptacle having a plurality of upstanding partitions and having an inking surface in the bottom thereof, and a member having a type surface, said member having an enlarged upper portion adapted to engage adjacent partitions to support said member 115 thereon with the type surface in contact with said inking surface.

11. In a device of the character described, a receptacle having a plurality of upstanding partitions and having an inking surface in the bottom thereof, and a member having a type surface, said member having an enlarged upper portion adapted to engage adjacent partitions to support said member 120 thereon with the type surface in contact with said inking surface.

- fact with said inking surface, said partitions having cut-out portions to permit grasping said member beneath said enlarged portion.
12. In a device of the character described, 5 a casing, partitions dividing the interior of said casing into stalls, each adapted to receive a single stamp, stamps, a removable inking pad adapted to form the base of all of said stalls, and means independent of said 10 pad for supporting said stamps in contact with said pad.
13. In a device of the character described, 15 a casing, partitions dividing the interior of said casing into stalls, each adapted to receive a single stamp, stamps, a slideable inking pad adapted to form the base of all of said stalls, and means independent of said pad to support said stamps in contact with said pad.
14. In a device of the character described, 20 a casing, partitions dividing said casing into stalls, stamps, adapted to be received in said stalls, an ink pad forming a base for said stalls and adapted to slide in and out of said 25 casing, and means including said stamps to limit the sliding movement of said pad.
15. In a device of the character described, 30 a casing, partitions dividing said casing into stalls, stamps adapted to be received in said stalls, an ink pad forming a base for said stalls and adapted to slide in and out of said
- casing, and a flange upon said pad adapted to engage a stamp within a stall to limit the sliding movement of said pad.
16. In a device of the character described, 35 a casing, partitions dividing said casing into stalls, each adapted to receive a single stamp, stamps, a slideable inking pad forming a base for said stalls, means independent of said pad for supporting said stamps in 40 contact with said pad, and alternative means for supporting said stamps out of contact with said pad.
17. In a device of the character described, 45 a casing, partitions dividing said casing into stalls, each stall adapted to receive a single stamp, stamps, a sliding ink pad forming a base for said stalls, means independent of said pad for supporting said stamps in contact with said pad, and alternative resilient 50 means for supporting said stamps out of contact with said pad.
18. In a device of the character described, 55 a casing, partitions dividing said casing into stalls, each stall adapted to receive a single stamp, stamps, a slideable ink pad adapted to form a base for said stalls, and resilient means carried by the casing to prevent shifting of the stamps within the stalls.

This specification signed this 4th day of 60
February, 1922.

ISADORE J. FAGGEN.
